ACCESSORY TOILET CHAIR

Florence G. Mills, Los Angeles, Calif.

Application May 2, 1955, Serial No. 35,762

Term of patent 14 years

(Cl. D4—5)

FIG. 1.

FIG. 2.

FIG. 3.

The broken line structure in Figure 1 is shown for illustrative purposes only.

I claim:

The ornamental design for an accessory toilet chair, as shown and described.
